UNITED STATES PATENT OFFICE.

HENRY G. BUTLER, OF KENOSHA, WISCONSIN, ASSIGNOR TO SHNABLE & QUINN, OF CHICAGO, ILLINOIS, A COPARTNERSHIP COMPOSED OF EMILE R. SHNABLE AND JOHN B. QUINN.

EXCAVATOR-SHOVEL.

1,070,405.

Specification of Letters Patent.

Patented Aug. 19, 1913.

Application filed February 21, 1910. Serial No. 545,086.

To all whom it may concern:

Be it known that I, HENRY G. BUTLER, a citizen of the United States, residing at Kenosha, in the county of Kenosha and State of Wisconsin, have invented certain new and useful Improvements in Excavator-Shovels, of which the following is a specification.

This invention relates in general to excavator buckets and more particularly to that type of buckets or shovels having an open front with a forward cutting edge and which are manipulated by means of pulling and hoisting cables.

One of the principal objects of my invention is the provision of a bucket adapted to discharge or dump from the rear end and having a closure for normally closing the rear end of the bucket body during the loading and hoisting operations.

My invention further aims to provide a bucket which will be automatically closed and retained in closed position by a pull upon the draft member or drag line.

Other objects and advantages of the present invention will be apparent as the same becomes better understood by reference to the following description when considered in connection with the accompanying drawings illustrating those practical embodiments of the invention which at the present time appear to be preferable constructions.

On the drawings—Figure 1 is a side elevation of a bucket or shovel embodying my invention, showing the same in closed position; Fig. 2 is a view similar to Fig. 1 showing the bucket in open or dumping position; Fig. 3 is a transverse sectional view through the rear portion of the bucket shown in Fig. 1; and Fig. 4 is a fragmentary side elevation of a bucket showing another manner of connecting the bucket body and the frame or cradle.

Throughout the various figures of the drawings similar reference characters indicate like parts.

From an inspection of the drawings it will be observed that the bucket body A is pivotally mounted to swing in a vertical plane on the frame or cradle B, the rear end of the frame B being provided with a closure L adapted to close the rear open end of the bucket body when the bucket body and frame assume the relative positions shown

in Figs. 1 and 4. The bucket is raised and lowered as a whole by a hoisting cable I attached to the top of the frame B and connected with any suitable hoisting mechanism. A draft member or drag line by means of which the bucket is pulled forward in the loading operation and is held in closed position so long as the pull is exerted thereon, is connected by the portions C with both the frame and the bucket body. In Figs. 1, 2 and 3 a sliding connection is afforded between the bucket body and the portion C through pulleys or sheaves F fixed to the sides of the body, the ends of the portion C being passed over pulleys D mounted on the frame and secured to the body A at the points E.

When the bucket is lowered and tension is exerted upon the portions C the rear end of the bucket body will be elevated into engagement with the closure L and will be retained in that position after the bucket has been filled so long as tension is maintained upon the member C. When the draft member is slackened the weight of the rear end of the bucket and the load carried thereby will cause said rear end to fall into the position shown in Fig. 2, so that the load will be dumped. The opening movement of the bucket is limited by stops or abutments H which engage with the upright portions of the frame B.

In Fig. 4 the pulley D and the fixed point E are reversed so that a sliding connection between the bucket body and the member C is also afforded at the rear end of the bucket, the fixed connection E being the connection between the members C and the rearwardly extending portion of the frame.

It is believed that my invention and its mode of operation will be understood from the foregoing without further description and it will be manifest that various changes in the mechanical details of construction may be resorted to without departing from the spirit of the invention or sacrificing any of the material advantages thereof.

I claim:

1. In an excavator bucket, the combination of a bucket body having a forward cutting edge and an open rear end, a closure for said rear end pivotally connected with said bucket body, a draft member, operative connections between said draft member and the front end of the bucket, and a connec-

- tion between said draft member and the rear end of the bucket body to hold the bucket in closed position under pull on said draft member.
5. In an excavator bucket, the combination of a frame, a closure carried thereby, a bucket body pivoted on said frame, a draft member connected with the front end of the bucket body, and means connecting said draft member with the frame and the rear of the bucket body whereby the bucket is held in closed position under pull on said draft member.
10. In an excavator bucket, the combination of a frame, a closure carried thereby, a bucket body pivoted on said frame, a draft member connected with the front end of said bucket body, a pulley mounted on the frame, and connections between the rear of said bucket body and the draft member having traveling engagement with said pulley whereby the closure and rear end of the bucket body are maintained in coöperative relation by tension exerted on said draft member.
15. In an excavator bucket, the combination of a frame, a closure carried thereby, a bucket body pivoted on said frame, a draft member connected with the front end of said bucket body, a pulley mounted on the frame, and connections between the rear of said bucket body and the draft member having traveling engagement with said pulley whereby the closure and rear end of the bucket body are maintained in coöperative relation by tension exerted on said draft member.
20. In an excavator bucket, the combination of a frame, a closure carried thereby, a bucket body pivoted on said frame, a draft member, and connections between said bucket body at the rear of the pivotal connection and the draft member and engaged with the frame for holding the bucket in closed position under pull on the draft member.
25. In an excavator bucket, the combination of a bucket body having a forward cutting edge and an open rear end, a frame on which said body is pivoted, said frame being provided at its rear end with a closure adapted to close the open rear end of the body, and means slidingly engaged with the frame and attached to the rear end of said bucket whereby the bucket is held in closed position by tension exerted upon said means and is permitted to open when the tension is released.
30. In mechanism of the character described, the combination with supporting means, of a shovel member open at both ends and pivotally attached about an axis intermediate between such ends to said means, the center of gravity of said shovel being so located as to cause the same when loaded to tend to tilt backwardly about its pivotal axis, a gate carried by said means and adapted to close the rear end of said shovel in the raised position of the latter, hauling means attached to said shovel, and flexible means passing over a part of said supporting means and connected both to said hauling means and to said shovel back of its center of gravity for controlling the tilting of said shovel.
35. In mechanism of the character described, the combination with supporting means, of a shovel member open at both ends and pivotally attached about an axis intermediate between its ends to said means, the pivotal axis of said shovel lying between the shovel's cutting edge and a point immediately back of the center of gravity of said shovel, a gate carried by said means and adapted to close the rear end of said shovel in the raised position of the latter, hauling means attached to said shovel, and flexible means passing over a part of said supporting means and connected both to said hauling means and to said shovel back of its center of gravity for controlling the tilting of said shovel.
40. In mechanism of the character described, the combination with supporting means, of a shovel member open at both ends and pivotally attached about an axis intermediate between its ends to said means, the pivotal axis of said shovel lying between the shovel's cutting edge and a point immediately back of the center of gravity of said shovel, a gate carried by said means and adapted to close the rear end of said shovel in the raised position of the latter, hauling means attached to said shovel, and means located on the opposite side of the pivotal axis from the cutting edge of the shovel for variably governing the tilting of said shovel.
45. In an excavator bucket, the combination of a bucket body having a forward cutting edge and an open rear end, a closure for said rear end, a draft member, operative connections between said draft member and the rear end of the bucket, and a connection between said draft member and the rear end of the bucket body to hold the bucket in closed position under pull on said member.
50. In mechanism of the character described, the combination with supporting means, of a shovel member open at both ends and pivotally attached about an axis intermediate between such ends to said means, the center of gravity of said shovel being so located as to cause the same when loaded to tend to tilt backwardly about its pivotal axis, a gate carried by said means and adapted to close the rear end of said shovel in the raised position of the latter, hauling means attached to said shovel, and means for variably governing the tilting of said shovel attached to the shovel back of its center of gravity.
55. In mechanism of the character described, the combination with supporting means, of a shovel member open at both ends and pivotally attached about an axis intermediate between such ends to said means, the center of gravity of said shovel being so located as to cause the same when loaded to tend to tilt backwardly about its pivotal axis, a gate carried by said means and adapted to close the rear end of said shovel in the raised position of the latter, hauling means attached to said shovel, and means for variably governing the tilting of said shovel attached to the shovel back of its center of gravity.
60. In mechanism of the character described, the combination with supporting means, of a shovel member open at both ends and pivotally attached about an axis intermediate between such ends to said means, the center of gravity of said shovel being so located as to cause the same when loaded to tend to tilt backwardly about its pivotal axis, a gate carried by said means and adapted to close the rear end of said shovel in the raised position of the latter, hauling means attached to said shovel, and means for variably governing the tilting of said shovel attached to the shovel back of its center of gravity.
65. In mechanism of the character described, the combination with supporting means, of a shovel member open at both ends and pivotally attached about an axis intermediate between such ends to said means, the center of gravity of said shovel being so located as to cause the same when loaded to tend to tilt backwardly about its pivotal axis, a gate carried by said means and adapted to close the rear end of said shovel in the raised position of the latter, hauling means attached to said shovel, and means for variably governing the tilting of said shovel attached to the shovel back of its center of gravity.

supporting member, pull on said draft member serving to hold the bucket body in closed relation to said closure.

12. In an excavator bucket, the combination of a bucket body having a forward cutting edge and an open rear end, a bucket supporting member to which the sides of the bucket body are pivoted, a closure for the rear end of said bucket body connected to said supporting member, and a draft member operatively connected to the front end of the bucket body and also connected with the rear end of said body and with said supporting member, said draft member under pull thereon being adapted to hold the bucket body in closed relation to said closure.

13. In an excavator bucket, the combina-

tion of a bucket body having a forward cutting edge and an open rear end, a bucket supporting member pivotally connected to the sides of the bucket body, a closure for the rear end of said bucket body connected with said supporting member, and means connecting the rear end of said body and said supporting member for elevating the rear end of the body into closed relation with said closure when pull is exerted upon said means.

In testimony whereof I affix my signature 30
in presence of two witnesses.

Correction in Letters Patent No. 1,070,405.

It is hereby certified that in Letters Patent No. 1,070,405, granted August 19, 1913, upon the application of Henry G. Butler, of Kenosha, Wisconsin, for an improvement in "Excavator-Shovels," an error appears in the printed specification requiring correction as follows: Page 2, line 117, for the word "rear" read *front*; and that the said Letters Patent should be read with this correction therein that the same may conform to the record of the case in the Patent Office.

Signed and sealed this 30th day of September, A. D., 1913.

Acting Commissioner of Patents.

supporting member, pull on said draft member serving to hold the bucket body in closed relation to said closure.

12. In an excavator bucket, the combination of a bucket body having a forward cutting edge and an open rear end, a bucket supporting member to which the sides of the bucket body are pivoted, a closure for the rear end of said bucket body connected to said supporting member, and a draft member operatively connected to the front end of the bucket body and also connected with the rear end of said body and with said supporting member, said draft member under pull thereon being adapted to hold the bucket body in closed relation to said closure.

13. In an excavator bucket, the combina-

tion of a bucket body having a forward cutting edge and an open rear end, a bucket supporting member pivotally connected to the sides of the bucket body, a closure for the rear end of said bucket body connected with said supporting member, and means connecting the rear end of said body and said supporting member for elevating the rear end of the body into closed relation with said closure when pull is exerted upon said means.

In testimony whereof I affix my signature 30
in presence of two witnesses.
